UNITED STATES PATENT OFFICE

95,576

DESIGN FOR A BOTTLE

George M. Brenner, Oak Park, Ill.

Application February 8, 1935, Serial No. 55,319

Term of patent 7 years

To whom it may concern:

Be it known that I, George M. Brenner, a citizen of the United States, residing at 724 Highland Ave., city of Oak Park, in the county of Cook and State of Illinois, have invented a new, original, and ornamental Design for Bottles, of which the following is a specification, reference being had to the accompanying drawing, forming part thereof.

I claim:

The ornamental design for a bottle, as shown.

GEORGE M. BRENNER.
